WINDOW LOCKING MEANS

Original Filed April 2, 1941

UNITED STATES PATENT OFFICE

2,467,032

WINDOW LOCKING MEANS

Jesse Hill, New York, N. Y.

Substituted for abandoned application Serial No.
386,417, April 2, 1941. This application April
9, 1946, Serial No. 660,633

1 Claim. (Cl. 292—67)

1

The present application is a substitute for abandoned application, Ser. No. 386,417, filed by applicant April 2, 1941.

The invention relates to new and useful improvements in window locking means, and it has for its object to provide a device, whereby a window may be left in a partly open position, and at the same time be securely locked.

As the construction of my device may well be said to be absolutely fool-proof, and as the said device is of a sturdy and yet simple construction, which would entail but a small manufacturing cost, it is thought that this device will be assured a great market.

With the above and other objects in view, this invention consists of the novel features of construction, combination, and arrangement of parts hereinafter fully described, claimed and illustrated in the accompanying drawings forming part of this specification, and in which similar characters of reference indicate corresponding parts in all views, and in which:

Figure 1 is a perspective view of my invention applied to a window, and with the top sash partly open.

Figure 2 shows a top plan view of my invention in a locked position.

Figure 3 is a front elevational view of my device, as shown in Figure 2.

Figure 4 is a view similar to Figure 2, showing the key member in the process of being unlocked.

Figure 5 is a top plan view, showing the key member in an unlocking operation.

Figure 6 is a perspective view of the key member proper.

Referring more particularly to the drawings, 10 indicates a window frame having the sashes 11 and 12.

A plate 13, of any suitable material, and provided with a number of notches therein, as indicated by 14, is secured to one of said sashes, preferably the upper one.

Upon the other sash 12, at the top thereof, is arranged a plate member 15 secured thereto by means of screws 16; said plate member is formed with a bridge 17 upon the outer end of which a stud 18 is fixedly disposed, while upon the inner end of said bridge is arranged another stud or bolt 19.

A sliding member 20, which may appropriately be termed a key member, consists of a plate formed with a longitudinal slot 21 adapted to slidably receive therein the stud 18; said key member has another slot 22 which is open at the inner end thereof; said construction may be especially noted in Figure 6. The key member 20 is upon the inner end thereof formed with an upward bend or end portion 23, which serves a double purpose, namely, first, that of a means for operating the sliding member 20 with respect

5 to the sash plate 13; and, secondly, that of locking the key member in a fool-proof position, when said key member after being adjusted with respect to the sash plate 13 is pulled back or inwardly, as shown in Figure 1. In this latter case the parts can not become unlocked before the key member 20 is pushed forward and the end portion 23 thereof passes over, or clears the stud 19, in which instance said stud 19 will become disengaged from the slot 22, thereby permitting the key member to turn upon the stud 18 and thus become disengaged from the sash plate 13.

10 The studs or bolts 18 and 19 are formed with heads 24 thereon in order to slidably secure the key member 20 to the plate member 15.

15 The end portion 23 may further, as shown in Figure 6 have the elongated slot 22 terminate in the shape of the head of the stud 19 in order to obtain a possibly still more secure engagement of these parts when in locked position.

20 It is obvious that slight changes may be made in the form, construction and arrangement of the several parts, as shown, within the scope of the appended claims, without departing from the spirit of the invention, and I do not, therefore, wish to limit myself to the exact construction and arrangement shown and described herein.

25 What I claim as my invention, and desire to secure by Letters Patent of the United States is:

30 A window locking device adapted to coact with, a notched plate secured to a window sash, and comprising a plate member formed with a bridge portion and being arranged on top of a second window sash, a stud fixedly arranged upon the 35 outer end of said bridge portion, and a stud fixedly arranged upon the inner end thereof, a key member having slots therein adapted to slidably receive said studs, heads formed on said studs and adapted to secure a permanent connection 40 of the plate member with the key member, an upward bend formed at one end of the latter end embodying therein an elongation of one of said slots, whereby to receive one of the studs, when in locked position, said key member being turnable upon the other stud in disengaging said key member from the notched plate.

45 JESSE HILL.
